UNITED STATES PATENT OFFICE.

DAVID V. HOWELL, OF MONROE, NEW YORK.

WASHING MACHINE.

Application filed June 30, 1919. Serial No. 307,604.

To all whom it may concern:

Be it known that I, DAVID V. HOWELL, a citizen of the United States, and a resident of Monroe, in the county of Orange and State of New York, have invented new and useful Improvements in Washing Machines, of which the following is a specification.

This invention relates to dish washing machines and has for its primary object the provision of a means whereby the cleansing agent employed may be so agitated as to cleanse or wash the dishes as a result of the contact of the cleansing agent with the dishes.

A further object of the invention is to provide in a machine of the above mentioned character a means whereby the dishes may be easily and quickly raised or lowered from the receptacle adapted to receive the cleansing agent.

A further object of the invention is to provide a machine of the above mentioned character which is simple in construction, inexpensive to manufacture and reliable in operation.

Other objects and advantages of the invention will be apparent during the course of the following description taken in connection with the accompanying drawings.

In the drawings, forming a part of this specification wherein like numerals are employed to designate like parts throughout the same,

Figure 1 is a perspective view of the device embodying my invention, and,

Figure 2 is a detail view of the operating mechanism employed, certain elements thereof being shown in section.

In the drawings, wherein for the purpose of illustration is shown a preferred form of my invention, the numeral 5 indicates a preferably cylindrical receptacle adapted to receive therein a suitable quantity of cleansing agent such as hot water having a suitable

amount of soap in solution to facilitate the removal of dirt or grease from the dishes desired to be cleansed. To the sides of the receptacle 5 there is suitably secured a vertically disposed U-shaped supporting member 6, the supporting member 6 having its depending arms secured to the receptacle 5 by means of rivets or bolts as shown at 7. Upon the U-shaped member 6 substantially intermediate its ends there is disposed a second U-shaped yoke 8 having its ends bent substantially to right-angles and secured to the

U-shaped member 6 by means of rivets or the like as shown at 9. Within the vertically disposed U-shaped member 8 there is journaled a rotatable shaft 10 provided with 60 collars 11 which are adapted to prevent longitudinal movement of the shaft 10 within its supporting yoke 8. The shaft 10 is extended an appreciable distance and is provided at its extension with a crank or handle 12 by means of which rotation is imparted to the shaft 10. To the shaft 10 there is suitably secured a bevel gear 13 which meshes with a relatively small bevel gear 14, the bevel gear 14 being provided on its under face with a channel or groove 15 adapted to receive a plurality of ball bearings 16 arranged within a groove 17 of a supporting base 18 which is suitably secured to the U-shaped member 6 substantially intermediate 75 the angularly bent portions of the U-shaped yoke 8. To the gear 14 there is centrally secured a depending shaft 19 which projects downwardly through the supporting base 18 and a relatively large opening provided in 80 the U-shaped member 6, the relatively large opening being indicated by the numeral 20. To the lower end of the shaft 19 there is connected a chain 21 constructed of preferably square links. To the chain 21 there is connected a hook 22 which is adapted to receive a plurality of preferably wire handles 23 connected as clearly shown in Figure 1 to the corners of a wire gauze basket 24, the basket being preferably rectilinear in shape 85 as is shown in Figure 1 and adapted to rotate within the receptacle 5 when power is applied to the handle 12. In use, the dishes which are to be cleansed are placed within the basket or receptacle 90 24 which is then hung upon hook 22 and suspended within the receptacle 5 which carries therein a suitable quantity of water or other cleansing agent to completely cover the dishes. The gear 13 is then rotated by 95 the means hereinbefore described, causing rotation of the shaft 19 through the instrumentality of the gear 14 carried thereby. When the shaft 19 is rotated the basket or receptacle 24 carrying the dishes therein is 100 likewise rotated, agitating the cleansing agent within the receptacle 5 and due to the swift movement of the dishes through the cleansing agent the dirt or grease is removed therefrom. It might be necessary 110 to rotate the basket 24 alternately in opposite directions to produce the most satis-

factory cleansing effect. The construction of the device as a whole is of such a nature, as is apparent, as to permit alternate, opposite rotation of the basket 24.

5 It is apparent that because of the peculiar situation of the ball bearings 16 the weight of the dishes within the receptacle or basket 24 is supported thereby and consequently the machine as a whole is more easily operated by hand than would otherwise be possible. It is further apparent that the ball bearings 16 confined between the gear 14 and the supporting base 18 are protected from dirt or grit because of the depending 10 flange carried by the gear 14, the flange being clearly shown in Figure 2 and adapted to snugly fit the peripheral edge of the supporting base 18. The depending flange not only serves as a means for protecting the ball bearings 16 from dirt or grit but serves further as a means for confining any desired lubricant between the gear 14 and the supporting base 18, the lubricant being used 15 as a means for lubricating the ball bearings 20 16 and the depending shaft 19. An important advantage of the flexible connection between the hook 22 and the shaft 19, 25 is that by means thereof, shocks upon the dishes in the receptacle 24 are prevented,

should power be suddenly applied tending 30 to rotate said basket.

It is to be understood that the form of my invention herewith shown and described is to be taken as a preferred example of the same, and that various changes in the shape, 35 size and arrangement of parts may be resorted to without departing from the spirit of the invention or the scope of the subjoined claim.

Having thus described my invention, what 40 I claim as new and desire to secure and protect by Letters Patent of the United States, is:

A dish washing machine comprising a receptacle, a supporting member secured thereto, a yoke supported by said member above the receptacle, a gear rotatably mounted in said yoke, means whereby said gear may be actuated, a second gear rotatably mounted on said supporting member and meshing 45 with the first gear, a shaft depending from said second gear, a hook having a flexible connection with the lower end of said shaft, and a foraminous receptacle having supporting means positioned to engage said 50 hook.

DAVID V. HOWELL.
